UNITED STATES PATENT OFFICE.

WILLIAM S. HADAWAY, JR., OF NEW ROCHELLE, NEW YORK, ASSIGNOR TO THE CUTLER-HAMMER MFG. CO., OF MILWAUKEE, WISCONSIN, A CORPORATION OF WISCONSIN.

ELECTRIC WATER-HEATER.

1,281,158.

Specification of Letters Patent.

Patented Oct. 8, 1918.

Application filed February 28, 1914, Serial No. 821,816. Renewed December 20, 1915. Serial No. 67,955.

To all whom it may concern:

Be it known that I, WILLIAM S. HADAWAY, Jr., a citizen of the United States, residing at New Rochelle, in the county 5 of Westchester and State of New York, have invented new and useful Improvements in Electric Water-Heaters, of which the following is a full, clear, concise, and exact description, reference being had to the accompanying drawing, forming a part of this specification.

This invention relates to electric water heaters.

The objects of the invention are:

15 To provide a water heater of improved construction, particularly adapted to heat quickly small quantities of water.

20 To provide a device which lends itself to economical manufacture and to ready assembly.

To provide an improved electric water heater, in which the electric heating unit is readily removable for repairs or replacement.

25 To provide a construction which permits convenient and ready access to the circuit terminals and switch.

30 To provide means for indicating, in an unmistakable manner, when the heating current is flowing and when it is turned off.

To provide a device which is efficient in operation and which is also neat, compact and ornamental.

35 Other objects and advantages of the invention will hereinafter appear.

For the purpose of describing my invention, I have illustrated in the accompanying drawings the preferred embodiment thereof, which is hereinafter explained in detail. It 40 is to be understood, however, that the invention may be embodied in other forms and, therefore, is not limited to the details of construction shown and described.

Figure 1, of the drawings is a central sectional elevation of the preferred form of water heater.

Fig. 2, is a top plan view of the base, with the cover removed.

Fig. 3, is an elevation of the heating unit

with certain parts broken away to disclose the interior construction.

The device is provided with a suitable base plate 1, preferably circular in outline, which supports a plurality of vertical standards 2 of which there are three in the present instance. The standards are secured to the base by suitable screws 3 and have screw threaded engagement at their upper ends with a casting in the general form of a ring 4, which is supported by the standards.

Within the central opening of the ring 4, a tubular member or cylinder 5 is supported near its upper open end, preferably by sweating it in said opening. The lower end 65 of the cylinder 5 is closed, thereby adapting it to act as a heating chamber for the liquid with which it is to be filled.

The ring 4 also supports a suitable liquid reservoir 6, which is preferably in the form 70 of a glass globe of ornamental appearance. The globe is clamped in position between rubber gaskets 7, the upper gasket being pressed downwardly by a cover plate 8 suitably secured to the ring 4, by the screws 9, for example. The globe is provided with a suitable cover 10 of ornamental outline. A faucet 11 is also carried by the ring 4, which communicates through an opening 12 with the upper part of the heating chamber. 75

During operation, the heating chamber is entirely filled with water which may also fill the reservoir to a greater or less extent, depending upon conditions. The water in the heating chamber is electrically heated by a heating unit 13, the latter fitting within a tube or container 14. The container 14 is closed at the top but is open at the bottom, at the point where it passes through the bottom wall of the heating chamber to which it 80 is preferably integrally united, in any suitable manner. The heating unit, which is hereinafter more fully described in detail, may be of any suitable construction. The container 14 conforms, in cross sectional 85 shape to the shape of the heating unit, whereby the latter is adapted to slide into and out of the container for the purpose of

replacement or repair and whereby the outer surface of the unit is in close heat conducting relation with the container, when the parts are assembled. The container 14 is 5 also water tight, thereby keeping the fluid from the heating unit.

The chamber 5 has its upper end normally closed by a valve 15 which rests upon a seat formed on the support 4. This valve 10 has a circular depending wall 15* which extends down into the chamber 5 to keep the valve from being laterally displaced.

The only normal communication between the reservoir 6 and the heating chamber 5 15 is through a tube 16. This tube 16 has its upper end fastened to the valve and provides communication between the reservoir and the bottom of the heating chamber.

When the heating unit 13 is energized the 20 water in the heating chamber 5 is quickly heated, there being practically no circulation between the water in the heating chamber and the reservoir while the water initially in the heating chamber is being heated.

25 When the water in the heating chamber has been sufficiently heated, which takes only a short time, it may be drawn off through the port 12 and faucet 11 it being displaced from the bottom of the heating 30 chamber by cool water which passes from the reservoir down through the tube 16 to the bottom of the heating chamber.

The valve 15 prohibits the cool water in the reservoir from passing into the top of 35 the heating chamber so the only way it can reach the heating chamber is through the tube 16.

If the water in the heating chamber is not drawn off when it reaches a predetermined 40 temperature then it will raise the valve 15 and pass into the reservoir, and cool water will pass from the reservoir through the tube 16 into the bottom of the heating chamber.

45 The heating unit, which I employ in the preferred construction, is one made up of a sheet metal channel 17, having its flanges bent over to infold a resistor 18, suitably insulated by layers of mica 19. The resistor 50 is preferably of the slotted ribbon type, being doubled over upon itself, whereby its adjacent ends may be conveniently connected to suitable circuit terminals 20. With the ribbon folded over upon itself, two superimposed lengths of resistor are provided as 55 shown in Fig. 3, these layers being separated by the mica, which is also interposed between the layers and the sheet metal walls.

In some cases I inclose an additional strip 60 of metal 21 within the channel, which acts as a cover plate over which the flanges of the channels are bent so that the mica insulation and the slotted ribbon are pressed between the cover plate and the bottom of the

channel. Under other conditions, however, 65 the cover plate may be dispensed with.

In order to control the circuit to the electric heater, I provide a switch 22, which is mounted preferably on the base. The switch may be of any standard construction. I 70 have illustrated a two button snap switch. The switch is inclosed within an ornamental cover plate 23, which fits over and is suitably held to the base, the cover plate being provided with suitable openings, through 75 which the push buttons of the switch 22 may protrude. The cover plate 23 is also provided with an insulating bushing 24 through which the circuit conductors enter the enclosure within which the circuit terminals 80 are located. The cover plate is provided with an opening, in which a glass lens 25 of some distinctive color may be mounted, a small incandescent lamp 26 being mounted on the base beneath the lens, said lamp being 85 so connected in circuit that it will remain lighted while the heating current is on, thereby indicating unmistakably to the operator the fact that the current is flowing. This insures not only against waste of current after the desired quantity of water has 90 been heated, but insures also against the attainment of an excessive temperature, in case all of the liquid should be allowed to boil away.

95 The heating chamber may be provided with a short pipe or nipple 27, secured thereto, at the lower end thereof, whereby a more or less permanent connection may be established with a water pipe, so that the heating 100 chamber and reservoir may be filled simply by turning a valve. In the absence of such a connection the usual procedure is to remove the cover 10, and pour in the water from above.

105 The above described construction permits the glass globe to be readily removed from the supporting ring 4 whenever necessary and permits the ready replacement thereof in case of breakage. The heating chamber 110 is suspended from the ring 4 and is not used as a support for the ring, the ring being supported independently by the rods or standards 2. Convenient access may be had to the different parts located beneath the 115 cover plate of the base by simply lifting the cover plate which slides upwardly along the standards, the latter passing through suitable openings therein. The heating unit may be removed by removing the screws 3 to 120 detach the base from the standards, whereupon the unit may be readily slipped out of its container and as readily replaced therein.

125 As previously stated the invention is not limited to the details of the present construction and accordingly I desire to cover, as falling within the scope of the invention, whatever equivalent constructions may be

devised, wherever the modifications fall within the scope of the appended claims.

Having thus described my invention what I claim as new, and desire to secure by Letters Patent of the United States is:

1. A liquid heater having a reservoir, a heating chamber, a tube extending from the reservoir into the heating chamber to deliver liquid from the reservoir to the bottom of the chamber, a self-centering valve secured to the top of said tube and preventing liquid from reaching the chamber except through the tube, a faucet communicating with the upper end of said chamber for withdrawing the heated liquid therefrom, and a readily removable heater extending within the chamber. 65
2. An electric water heater comprising a base, a plurality of vertical standards thereon, a supporting ring mounted on the top of said standards, a heating chamber depending from said ring and arranged between said standards, a circulation tube supported from said ring and extending nearly to the bottom of said heating chamber, a metallic container closed at the top and passing through the bottom wall of said heating chamber, a heating unit having a sliding fit within said container and having its lower end, which projects beyond said container, deflected at a right angle, circuit terminals arranged on said deflected end, a circuit controlling switch mounted on said base, a signal lamp also mounted thereon and connected in the heating circuit, a cover plate for said base, beneath which the various parts mounted on said base are concealed, the said cover plate being arranged to slide on said standards to expose the parts arranged beneath the same, and having an opening adjacent to said lamp, whereby the latter may indicate when the heating current is off or on. 70
3. A liquid heater having a base, a support located above and carried thereby, a reservoir located above and carried by said support, a heating chamber carried by and depending from said support, a valve between said reservoir and said chamber, a tube depending from said valve and providing communication between said reservoir and said chamber whereby liquid from the reservoir enters the chamber at the bottom, a faucet at the upper end of said chamber for withdrawing the heated liquid therefrom, and an electric heater extending into said chamber to heat the liquid therein. 75
4. A liquid heater having a reservoir, a heating chamber, a heater therefor, a support carrying both the reservoir and the chamber, a base upon and above which the support is mounted, a tube extending from the reservoir to the bottom of the chamber, the upper end of said tube coöperating with said support to form a valve to prevent liquid reaching said chamber except through said tube to practically isolate small quantities of the liquid within the heating chamber, and an outlet communicating with the upper end of the chamber for withdrawing the heated liquid therein. 80
5. An electric water heater comprising a reservoir, a heating chamber communicating with said reservoir, a circulating tube communicating with said reservoir and extending into the heating chamber in coaxial relation therewith, a relatively long, thin, flat metal tube projecting into said chamber at one side of said circulating tube and substantially parallel therewith, the inner end 85 of said flat metal tube being closed and the outer end being open and being fixed in the wall of said chamber, and a metal incased electric heating unit having a cross section corresponding to the cross section of the flat metal tube and fitting within said tube with a sliding fit whereby it is frictionally held in said tube in good heat conducting relation thereto and is readily removable therefrom. 85
6. An electric water heater comprising a reservoir, a heating chamber communicating therewith, a circulating tube communicating with said reservoir and extending into the heating chamber, a relatively long, thin, flat metal tube projecting into said chamber in substantially parallel relation with said circulating tube, the inner end of said flat metal tube being closed and the outer end being open and being fixed in one wall of said chamber and a metal incased electric heating 90 unit having a cross section corresponding to the cross section of the flat metal tube and fitting within said tube with a sliding fit whereby it is frictionally held in said tube in good heat conducting relation thereto and 100 is readily removable therefrom. 95
7. A liquid heater comprising a reservoir, a heating chamber located below the reservoir, a valve between the reservoir and chamber for preventing liquid from passing from the reservoir into the top of the chamber, a tube carried by said valve and providing communication between the reservoir and the bottom of the chamber, a heater extending into said chamber and readily removable therefrom; means for preventing the removal of the heater from opening the chamber, and an outlet at the top of said chamber for withdrawing the heated liquid therefrom. 110 115
8. A liquid heater comprising a base, supporting rods extending upwardly therefrom, a ring carried on the upper ends of said rods, a reservoir supported by and above said ring, a heating chamber open at its upper end and closed at its lower end depending from said ring, a valve seating on said ring to prevent liquid from passing from said reservoir into the upper end of said chamber, a tube se- 120 125

cured to and depending below said valve to convey liquid from the reservoir to the bottom of the chamber, an outlet at the top of said chamber, and a heating element projecting within said chamber from its closed end and readily removable therefrom.

5 In witness whereof, I have hereunto sub-

scribed my name in the presence of two witnesses:
